UNITED STATES PATENT OFFICE

2,136,019

WHIPPING ROLLER COASTER

Anton Pfau, Portland, Oreg.

Application October 17, 1936, Serial No. 106,146

1 Claim. (Cl. 280—87.01)

Experience has shown that roller coasters, the rear wheel supports of which are secured against movement, are subject to being upset and overturned when the user thereof makes a sharp turn while traveling at a reasonable rate of speed. Furthermore, roller coasters embodying the presently known principles of construction have limited maneuverability and require considerable space for making a complete turn. It is within the contemplation of my invention to provide a coaster which eliminates the foregoing objections.

By incorporating the construction embodying the principles of my invention, it is possible to use the coaster not only as a means of coasting down steep grades, but also for the purpose of "whipping" the rear of the coaster by a sudden turn of the steering mechanism, thus providing an added thrill to the user of a coaster embodying my invention. It is obvious that the extent of the arc which the rear of the coaster will make in its "whipping" movement is directly proportional to the speed of the coaster and the degree of the turn made by the front end of the coaster. Experience has indicated that it is possible to make several loops with a coaster embodying the principles of my invention without upsetting the coaster during its travels. Furthermore, less space is needed in turning a coaster embodying my invention.

30 One of the objects of my invention is to provide a roller coaster possessing increased maneuverability.

Another object of my invention is to provide a roller coaster which possesses characteristics that insure against its being upset or overturned when the user thereof makes a sharp turn while traveling at great speed.

A still further object of the invention is to provide a roller coaster having a low center of gravity.

Another object of the invention is to provide a roller coaster, the front axle of which is braced to insure against shimming of the steering mechanism, while at the same time, providing a resilient assembly for the steering mechanism of the coaster.

Another object of the invention is to provide a coaster which is simple and durable in construction, which is inexpensive to manufacture and to maintain and which is attractive in appearance.

The invention is directed to other objects and possesses other features of advantage, a full understanding of which will become readily apparent from the following description and the accompanying drawing which illustrates the pre-

ferred form of embodiment by which the invention may be realized, and in which:

Figure 1 is a perspective view of a roller coaster embodying the principles of my invention.

Figure 2 is a sectional, front view of the coaster shown in Figure 1, graphically pointing out the details of construction of the steering mechanism.

Figure 3 is a sectional view, taken on line 3—3 of Figure 2 looking in the direction indicated, showing the manner in which the wheel and axle 10 supports are joined.

Figure 4 is a sectional, side view, taken on line 4—4 of Figure 2 looking in the direction indicated, which also shows the details of construction of the front end of the coaster embodying the principles of my invention.

Figure 5 is a fragmentary, plan view, taken on line 5—5 of Figure 2 looking in the direction indicated, showing the bracing members for the front axle assembly.

Figure 6 is an end view, taken on line 6—6 of Figure 1 looking in the direction indicated, showing the manner in which the braking members are retained against the side of the coaster embodying the principles of my invention.

Figure 7 is a side view of one of the rear wheels embodying the principles of my invention.

Like reference characters are employed to indicate like parts in the several views shown in the accompanying drawing.

An inspection of Figure 1 discloses a roller coaster having a top 10, which may be made of any desirable material and of any desirable dimensions. A front axle 12 has a pair of wheels 11 journaled thereto. An axle brace, having arms 13, 13A and 17 and top 14 is made of one piece of material as will be seen in Figure 5. This brace may be made of any material, but preference is given to a material which has some resiliency. Arms 13 and 13A are disposed in opposite relation to each other, and arm 17 is disposed at right angles to arms 13 and 13A. In Figure 2, it will be seen that arms 13 and 13A extend downwardly from the center portion 14, and each have a down turned portion 15 which are secured in any desirable manner to axle 12. Arm 17 incorporates a sharp bend 17A, as shown in Figure 4, and is also secured to axle 12 in any desirable manner.

In order to add greater stability to the front axle and in order to offer a bearing surface to the wheels 11, another brace member 18 is transversely disposed with relation to axle 12 and has at each end thereof upturned portions 19 which

50

55

are secured to the axle in any desirable manner. In order to prevent any friction between down turned portions 15 and upturned portions 19 and to provide a stable yet resilient front axle assembly, the upturned portions 19 are clinched against the upturned portion 15, as shown at 20 in Figures 3 and 4. By this construction, the front axle is braced against any transverse or rearward thrusts while, at the same time, there is provided the necessary resiliency for the front axle assembly.

A wearing washer 25 is secured in any desirable manner to the underside of the top 10 and is adapted to contact the center portion 14 of the bracing member. Elongated openings 16 are registerably disposed through the center portion 14 of the bracing member, the washer and the front end of top 10, as shown in Figure 4. A steering arm 21 also has an elongated opening 20 therethrough which coincides with elongated openings 16, when the steering arm 21 is positioned at the front portion of the top 10. The center portion 14 and steering arm 21 are cooperatively joined to each other by bolt 23 which passes through the elongated openings in each of these members and is retained therein by nut 24. A rope 22 may be secured to the ends of the steering arm 21.

The rear wheels' construction may best be seen 30 in Figure 7 which shows one of the rear wheels 26 journaled within one of the frames 27. The frame 27 is pivoted on a caster pivot 28, the construction of which is not shown. It is well to point out that any type of bearing may be inserted within the caster pivot, although a ball bearing is preferred. The important feature of this construction is to permit not only the rota-

tion of the rear wheels 26, but also the pivoting of the frame 27 to which the rear wheel 26 is journaled. The rear wheel assembly is secured to the top 10 through a plurality of bolts 29 and nuts 30.

A pair of brakes are secured to the sides of top 10. The description of one brake will suffice since both brakes are constructed in the same manner. A bar 32 extends transversely of the top 10, and a clamp 33 secures the bar to the 10 underside of the frame 10. Brake members 31 are pivoted with respect to the bar 32. In order to prevent the brake members 31 from contacting the road surface at all times, a spring 34 is placed between two washers and tensioned 15 against the side of the brake member 31 by nut 35 threaded upon bar 32.

The invention has been described in connection with a specific illustrated embodiment disclosing a definite arrangement of parts. However, it will be understood that changes may be made in the elements and in the arrangements of them without departing from the spirit of this invention.

Having thus described my invention what I 25 claim as new and upon which I desire to secure Letters Patent is:

Means for bracing the front axle of a roller coaster of conventional design against transverse and rearward thrusts comprising a unitary axle 30 brace having a top portion and three arms extending downwardly from said top portion, said arms being joined to the axle, and a second axle brace positioned transversely of and on the under side of and joined to the axle.

ANTON PFAU.
